UNITED STATES PATENT OFFICE

LESTER L. LADD, OF LOCKPORT, ILLINOIS

KILN FURNITURE

Application filed June 29, 1931. Serial No. 547,555.

This invention relates to kiln furniture used for supporting ceramic products. Certain types of ceramic products, such as dishes and other table ware, are subjected to three distinct firing operations. The bisque is first hardened in a bisque kiln and, after being hardened, it is glazed and the glost ware is then fired in a glost kiln. The glost ware may then be decorated and refired in a decorative kiln. The ceramic products are stacked in the kilns on racks which are commonly referred to as kiln furniture. These racks are made of a suitable refractory material.

No great degree of care need be exercised in stacking bisque ware in a bisque kiln, but in the glost kilns and decorating kilns considerable care in stacking must be exercised to avoid blemishes on the finished product.

Kiln furniture heretofore in use has not been entirely satisfactory because it has been difficult to quickly assemble and, when used in glost and decorating kilns, it has left blemishes upon the ware which are readily apparent to those skilled in this art.

The main objects of this invention are to provide kiln furniture of knock down construction having an improved form and arrangement of separable parts which may be easily and quickly assembled and dismantled; to provide kiln furniture having improved means whereby dishes and similar ware may be stacked on edge without marring the ware; and to provide improved means for detachably securing the parts together.

An illustrative embodiment of this invention is shown in the accompanying drawing, wherein,

Figure 1 is a fragmentary side elevation of a portion of a kiln showing some of the improved furniture.

Fig. 2 is a transverse section of a portion of a kiln employing the improved furniture.

Fig. 3 is a perspective view of one of the standards and Fig. 4 is a perspective view of one of the shelf sections.

Fig. 5 is a fragmentary perspective view of one of the saddles for supporting the ware on the shelves.

The improved kiln furniture to which this invention is applied is adapted for use in connection with many different types of kiln, and for this reason the accompanying drawing shows only as much of the kiln structure as will be helpful in apprehending the invention.

In the form shown, the kiln includes a firing chamber 1 enclosed by the usual housing 2 through which a conveyor platform 3 is moved for carrying the ceramic ware through the kiln.

The improved furniture comprises a plurality of horizontal shelf sections supported on upright standards. These separable parts may be of various sizes to accommodate large and small ware. In Figure 1, two different sizes of furniture are illustrated for use in connection with large plates 4 and smaller dishes 5.

In the old types of racks heretofore in use, the plates and dishes were supported horizontally in the stack. With the improved furniture herein shown, the plates and dishes are intended to be supported on edge. This permits them to be stacked more quickly than with the former types of racks.

In the construction shown, the improved furniture comprises supporting saddles 6, standards 7, pins 8 and shelf sections 9 and 9.1.

The saddles 6 are supported on the conveyor and shelf sections in pairs in substantially parallel spaced relation for supporting the plates and dishes on edge. The saddles are preferably grooved to form spaced seats 10 for the dishes. As shown in Fig. 4, the saddles are triangular in cross section, so as to

to present sharp edges to the dishes in order to prevent marring of the glazed ware.

The standards and shelf sections are made of refractory material and absorb heat from the kiln. In order to reduce the mass of refractory material and thereby increase the efficiency of the kiln, the standards are recessed as shown at 11 and 12 and the shelf sections are recessed as shown at 13.

The standards are provided with foot portions 14, and a row of apertures 15 in which the pins 8 are seated. The pins 8 project through both sides of the standard so that each pin is adapted to engage two dishes. The pins 8 are also triangular in cross section and they are positioned as shown in Fig. 3 so as to present sharp edges to the ware. These pins hold the dishes in spaced relation to one another and secure them against tilting.

In the construction illustrated, one edge of each of the shelf sections 9 is offset to form seats 16 which permit adjoining shelf sections to overlap as shown in Fig. 1. The end sections 9.1 need not be provided with these offset seats. Grooves 17 are formed in the lower faces of the shelf sections for interfitting engagement with the standards.

In operation each layer of the rack is set up and loaded with the ware before the next higher layer is constructed. With this improved form and arrangement of parts, the furniture may be quickly and easily set up and loaded or dismantled and unloaded, even while the conveyor platform, such as used in annular kilns, is in motion. With this type of furniture, in which the dishes are supported on edge, the end dishes of each stack may be positioned with their bottom sides facing outwardly, as shown in Fig. 2, thereby preventing heat and gases from injuring the ware. In the form shown, the movable conveyor forms the base for supporting the furniture, but it is obvious that the furniture may be supported on the base of any other type of kiln.

Although but one specific embodiment of this invention has been herein shown and described it will be understood that details of the construction may be altered without departing from the spirit of the invention as defined by the following claims.

I claim:

1. Kiln furniture comprising a base for supporting ceramic ware, a plurality of standards supported on said base in spaced relation to one another, each of said standards having a row of apertures therein, and pins detachably seated in said apertures, each of said pins projecting beyond opposite sides of its standard for engagement with the ware.

2. Kiln furniture comprising a plurality of horizontal shelves spaced apart one above another for supporting ceramic ware, a plurality of standards for supporting said

shelves, each of said shelves having a plurality of interfitting sections, one end of each section being supported on an adjacent standard and the other end of each section being supported on an adjoining shelf section, and horizontally disposed pins extending through said standards to secure the ware against tilting.

3. Kiln furniture comprising a plurality of shelf sections having interfitting edges, and a plurality of standards for supporting said sections, one edge of each section being supported on the upper end of an adjacent standard, the opposite edge of each section overlapping the adjoining section.
